TRACK FOR VEHICLES

Charles O. Slemmons, South Bend, Ind., assignor
to The B. F. Goodrich Company, New York,
N. Y., a corporation of New York

Application May 27, 1946, Serial No. 672,413

13 Claims. (Cl. 305—10)

1

This invention relates to track for self-laying track type vehicles and is especially useful on track vehicles to be operated over soft or rough ground at high speed.

The principal objects are to provide good distribution of the supported load, to provide for full effectiveness of rubber or the like in load-supporting pads, to provide broad contact with the ground, to prevent spreading of the cushioning means, to provide a smooth path for the bogie wheels, to provide high resistance to lateral bending, to provide good flexibility and to provide quiet operation.

These and other objects will appear from the following description and the accompanying drawings.

Of the drawings,

Fig. 1 is a partial side elevation of a track constructed in accordance with and embodying the invention, with one of the driving and one of the bogie wheels about which it is trained in driving a vehicle, other parts being broken away.

Fig. 2 is a view of the wheel-contacting face of a portion of the track.

Fig. 3 is a cross-sectional view thereof, taken on line 3—3 of Fig. 2, the bogie wheels being indicated in dot and dash lines.

Fig. 4 is a longitudinal sectional view thereof, taken on line 4—4 of Fig. 3.

Referring to the drawings, the numerals 10, 11 designate substantially inextensible endless bands widely spaced apart and arranged in parallel relation. Each band includes a layer of inextensible flexible reinforcing elements 12, preferably of metallic cable, arranged in parallel reaches spaced from each other laterally of the band and completely separated and surrounded by a body 13 of resilient rubber or other rubber-like material to which the element is secured by a bond resulting from vulcanization of the body of rubber-like material.

For securing the bands to the other parts of the track, each band has embedded therein at regular intervals along its extent, pairs of opposed stirrup straps 14, 15, each having central portions opposed to but spaced from the reinforcing elements 12 by the rubber-like cushioning material, and offset ear-like ends 16, 17 which protrude from the bands at the sides thereof and are perforated for securing them to shoes 18 as by means of rivets 19. The ends of the straps 16, 17 are offset oppositely to bring their ends into face to face relation and to provide space for clearing the cushioned reinforcing elements.

2

Secured to the bands 10, 11 as by the rivets 19, the shoes 18 are arranged cross-wise of the bands and are slightly spaced-apart longitudinally of the bands so as not to interfere with each other.

5 The shoes may be of light weight metal construction and may be formed of sheet metal, although castings or forgings may be used if desired. Each shoe extends laterally beyond the bands at each side to provide broad contact with the ground and has upwardly inclined ends 20, 21 to assist operation on soft ground and in turning.

Each shoe is formed with an upwardly directed protuberance 22 at its center for engaging between pairs of bogie wheels 23, 24 for guiding the track. These protuberances may also be used as driving lugs for engaging drive sprockets of the vehicle when positive drive is desired. The lugs 22 are preferably of hollow construction having side openings 25 communicating with their interiors to provide escape of mud. Openings 26 at each lug 22 are formed through the floor of the shoes for the same purpose.

Each shoe is formed between the bands 10, 11 and the lug 22 with a plurality of substantially rectangular openings 30 defined by vertical walls 31 extending from the tread face of the track to a position close to the wheel-engaging face. Cushion blocks 32 of resilient rubber or other rubber-like material fill the openings 30 and are preferably secured to the walls 31 by a bond resulting from vulcanization thereto. The blocks 32 extend to the tread face of the track so as to contact directly with the ground, and extend above the walls 31, as at 33.

35 For distributing the load of the bogie wheels over the full area of the blocks and preventing spalling of the blocks at their free margins, as well as providing a smooth path of the bogies, wheel-contacting deck plates 35 of metal extend entirely across the upper face of each block 32 and have downwardly turned front and rear margins 36 overhanging the walls 31 for smooth passage of the bogie wheels from block to block. The plates 35 are adhered to the upper faces of

40 the blocks 32 preferably by vulcanized bonding and provide smooth bearing surfaces to engage the bogie wheels 23, 24 which are preferably of the rubber-tired variety. The resilient rubber blocks 32 transmit the weight of the vehicle directly through them to the ground.

45 Because the walls 31 restrain lateral bulging of the rubber-like material substantially throughout its depth the blocks provide cushions of great load capacity. Also, because the metal of the walls 31 ordinarily will wear somewhat

faster than the rubber-like material, a face of the rubber-like material will always be present so that the track is operable on pavement without objectionable damage to the pavement, as well as upon soft ground where the metal surfaces take effect. The spacing of the deck plates 35 above the upper margins of the walls 31 provides for cushioning deflection as the load is transmitted from the deck plates through the rubber-like material. The projecting portions of the 10 blocks between the shoe and the plate are preferably rebated, as at 42, to prevent marginal pinching of the material.

For stiffening the shoes and providing increased traction, the shoes may be provided with cross ribs 40 which are adapted to sink into soft ground and provide greater traction.

Through openings 41 are formed in the shoes in the region of the bands 10, 11 to lighten the track and also to permit escape of mud.

The track is preferably made endless and the reinforcing elements 12 may be of a continuous cable wound in convolutions and embedded in a continuous band of the rubber-like material prior to vulcanization of the latter.

The shoes are made separately and attached to the bands at regular intervals. This construction facilitates manufacture and provides for ready replacement of individual shoes or bands.

The bands 10, 11 are ordinarily free from contact with the wheels of the vehicle and are free from wear from contact therewith, while their location near the side of the track provides stability against side bending or warping flexure of the track and ties the shoes to each other near their side margins.

Variations may be made without departing from the scope of the invention as it is defined by the following claims.

I claim:

1. A track for a self-laying track type vehicle having track-engaging wheels, said track comprising flexible bands arranged in parallel relation, and shoes secured to said bands at intervals therealong, said shoes having openings therethrough, resilient bodies of rubber-like material secured in said openings and exposed at the tread faces of the shoes, said bodies having portions projecting at the faces of the shoes in the region engaged by said wheels opposite said tread faces, and deck plates secured to the projecting portions of said bodies in floating spaced-apart relation to said shoes to transmit wheel loads directly to said bodies.

2. A track for a self-laying track type vehicle having track-engaging wheels, said track comprising flexible bands arranged in parallel relation, and shoes secured to said bands at intervals therealong, said shoes having openings therethrough, resilient bodies of rubber-like material secured in said openings and exposed at the tread faces of the shoes in the region engaged by said wheels, the walls of said shoes at said openings embracing the sides of said bodies substantially throughout the depth of the latter, said bodies having portions projecting at the faces of the shoes opposite said tread faces, and deck plates secured to the projecting portions of said bodies in floating spaced-apart relation to said shoes to transmit wheel loads directly to said bodies.

3. A track for a self-laying track type vehicle having track-engaging wheels, said track comprising a pair of flexible bands arranged in parallel relation, each band comprising a layer of flexible reinforcing elements, a body of resilient

rubber-like material about said elements, and straps of metal embedded in said body about said elements and projecting therefrom, shoes secured to said straps at regular intervals along said bands, each said shoe having an opening therethrough, a resilient body of rubber-like material secured in said opening and exposed at the tread face of the track, said body having a portion projecting at the face of the shoe in the region engaged by one of said wheels opposite said tread face, and a metal plate secured to the projecting portions of said body and overlying said body and said opening in floating spaced-apart relation to said shoe to transmit wheel loads directly to said body, plates of said shoes providing collectively a substantially continuous bogie-wheel bearing surface.

4. A track for a self-laying track type vehicle having track-engaging wheels, said track comprising a plurality of shoes, means connecting said shoes flexibly in series, said shoes having apertures through the same in the regions engaged by said wheels, bodies of rubber-like material in said apertures exposed at the ground-contacting faces of the shoes, the walls of said shoes at said apertures embracing said bodies substantially throughout the depth of the latter and restraining lateral spreading thereof under wheel-loads transmitted directly through said bodies, 20 and deck plate members mounted on said bodies in floating spaced relation to said shoes for transmitting wheel-loads directly to said bodies.

5. A track shoe for an endless band track for engaging bogie wheels of a vehicle, said shoe 35 having an aperture through the same in the region engaged by one of said wheels, a body of rubber-like material of less area than said shoe in said aperture exposed at the ground-contacting face of the shoe, the wall of said shoe at said 40 aperture embracing the sides of said body entirely about the same and substantially throughout the depth thereof and restraining lateral spreading of said body under wheel-loads transmitted directly through said body, and a deck structure mounted on said body in floating spaced relation to said shoe for transmitting wheel loads directly to said body.

6. A track shoe as defined in claim 5 in which said body comprises a projecting portion and said deck structure comprises a plate permanently secured to said portion.

7. A track block for a self-laying track type vehicle in which a series of blocks are movably connected for engagement by load-transmitting wheels of the vehicle, said block comprising a metal frame having walls extending to a tread face of the block in the region of the block engaged by said wheels, a filling of resilient material retained by said walls and exposed at said face, said filling projecting beyond the opposite face of said block, and a deck plate of less area than said block secured to the projecting face of said filling in floating spaced-apart relation to said frame for engagement with a load transmitting wheel.

8. A track block as defined by claim 7 in which said filling is permanently secured to said walls.

9. A track block as defined by claim 7 in which said filling is permanently secured to said deck plate.

10. A track block as defined by claim 7 in which said filling is permanently secured to said walls and said deck plate.

11. A track for a self-laying track type vehicle having load-sustaining wheels for engaging the

track, said track comprising flexible bands arranged in parallel relation, and shoes secured to said bands at close intervals, said shoes having openings therethrough of small area relative to the area of the soes in the region of engagement of said wheels, resilient bodies of rubber-like material of area corresponding to said openings extending through said openings and projecting therebeyond at the wheel-engaging face of the shoes, and deck plates secured to the projecting portions of said bodies, with the deck plates of adjacent shoes substantially meeting to provide a substantially continuous surface for engaging said wheels.

12. A track for a self-laying track type vehicle having a load-sustaining wheel for engaging the track, said track comprising connected track shoes, each shoe having an opening therethrough from the ground-engaging faces to the wheel engaging face of the track, a body of resilient material in said opening and projecting therefrom at the wheel-engaging face of the track and a deck plate mounted for floating movement on the projecting portion of said body and spaced from said shoe, the deck plates of said shoes being spaced closely in the longitudinal direction of the track and collectively providing a smooth surface for rolling engagement with said wheel.

5

13. A track shoe for a self-laying track type vehicle, said shoe having opposite wheel contacting and tread faces and comprising a retaining wall extending rigidly about the wheel-contacting portion thereof and substantially to both faces of the block, a filling of resilient rubber-like material retained by said wall, said filling being exposed at said tread face of the shoe and projecting therefrom at said wheel contacting face providing load transmission through the filling directly from face to face thereof while being restrained from spreading throughout substantially its entire depth by said retaining wall, and a deck plate mounted for floating movement on the projecting portion of said filling providing a smooth surface for rolling engagement with a load supporting wheel of the vehicle.
